(57) **CLAIM**

The ornamental design of a hitch receiver assembly with dual accessory brackets, as shown and described.

DESCRIPTION

FIG. 1 is a perspective view of the hitch receiver assembly with dual accessory brackets of the present invention; FIG. 2 is a front elevational view thereof; FIG. 3 is a left side elevational view thereof; FIG. 4 is a rear elevational view thereof; FIG. 5 is a right side elevational view thereof; FIG. 6 is a top plan view thereof; and, FIG. 7 is a bottom plan view thereof.

The broken line showing of environment is for illustrative purposes only and forms no part of the claimed design.
